(57) **CLAIM**

The ornamental design for an assembling toy as shown and described.

DESCRIPTION

FIG. 1 is a front view of an assembling toy of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a front perspective view thereof.

FIG. 8 is a sectional view thereof taken along section line 8-8 of FIG. 5; and,

FIG. 9 is a rear perspective view thereof showing the assembling toy in use.

The broken lines are for the purpose of illustrating portions of the article that form no part of the claim.

1 Claim, 9 Drawing Sheets
